MANDREL FOR BOX-MAKING MACHINES

Application filed July 11, 1931, Serial No. 550,159, and in Germany April 14, 1927.

Boxes especially the outer casings of match boxes, and similar articles generally are manufactured by winding round a mandrel a blank, generally a veneer strip, provided with 5 scores where the strip is to be folded, and by winding a paper strip provided with paste round the said veneer for keeping the same together. According to this invention for connecting the veneer to the mandrel, the latter is provided with a rigidly fixed tongue, which extends along the mandrel at a suitable distance therefrom so that there is a slot between the mandrel and the tongue, which slot extends from one of the corners of 10 the mandrel throughout the mandrel in an oblique direction and in which the strip of veneer is inserted. The provision of a slot of the said character involves many technical advantages that will hereafter be referred to.

20 In the accompanying drawing.—

Figure 1 shows diagrammatically as much of a machine for manufacturing outer casings for match boxes as is necessary to explain the invention, and

25 Figure 2 shows the mandrel in plan view. 1 is the mandrel round which the veneer together with the paper strip is wound. The said mandrel, which may be carried by a shaft 2 and rotated in the direction indicated by the arrow is bevelled transversely at one of its narrow sides and at this side a tongue 3 triangular in cross section is rigidly fixed to the mandrel 1 at some distance from the same. The said tongue extends longitudinally of the mandrel and completes the corner of the same, cut away. Tongue 3 is fixed to the mandrel only at its inner end and constitutes a slot extending through the whole mandrel.

30 The veneer strip 4 is fed from a magazine 5 by a slider 6, so that the fore end of the strip is pushed into the slot between the mandrel and the tongue. During the rotation of the mandrel an angular turn in the veneer is effected between the end inserted into the 35 said slot and the subsequent part of the veneer, the said turn being determined by a transverse score provided in the veneer. In this manner the veneer is caused to partake 40 in the rotary motion of the mandrel, during

which motion it may be forced against the mandrel in known manner by a smoothing roller (not shown).

Among the advantages gained by the provision of a slot extending through the whole 55 mandrel as described above, the following may be mentioned. If for some reason the veneer inserted into the slot should be broken off, the part of the strip remaining in the slot will be removed from the same by the strip 60 which is subsequently inserted into the slot, for which reason no clogging or stopping-up of the slot may be effected which otherwise would cause an interruption of the operation. Further, dust deposited in the slot by 65 the veneers and also paste, which is very often transferred from the connecting paper to the veneer strip, will not be able to choke the slot because the deposition is removed at the open end of the slot by the veneer 70 strips, while pushed into the slot. For the said reasons the slot will never be closed, so that inserting of the veneers is prevented.

I claim:

35 A mandrel for box-making machines, comprising a rotatable body having a corner cut away, a tongue secured at the cut away corner of the body and disposed in spaced relation to the latter to provide a slot extending in the direction of the axis of rotation of the 80 body and open at both sides of the latter for receiving and holding a box blank.

In testimony whereof I have hereunto affixed my signature.

BROR ANDERS EMIL JOHNSON.
